UNITED STATES PATENT OFFICE.

JOHN PIES AND SOPHIE PIES, OF ORANGEBURG, NEW YORK.

MAGNETIC PROTECTOR FOR SHIPS.

1,293,539.

Specification of Letters Patent. Patented Feb. 4, 1919.

Application filed July 20, 1917. Serial No. 181,688.

To all whom it may concern:

Be it known that we, JOHN PIES, a subject of the King of Hungary, resident of Orangeburg, county of Rockland, and State of New York, and SOPHIE PIES, a subject of the King of Hungary, resident of Orangeburg, county of Rockland, and State of New York, have invented certain new and useful Improvements in Magnetic Protectors for Ships, of which the following is a specification.

This invention relates to improvements in attachments to the hulls of ships, by means of which submerged torpedoes, mines and the like may be attracted and held at a distance from the hull of the vessel, rendering them innocuous, thereby preventing damage.

The principal object of the invention is to provide such devices in forms which may be applied to ships as presently constructed, without necessitating any material change in the hull thereof, and which includes the provision of extended buoyant elements whereby the magnetic attractors are held at a safe distance from the hull.

A further object is to charge the magnetic attractors with a current derived from generators carried on board the vessel as to cause the same to operate through a relatively wide range of action, the power of the magnets being sufficient to divert a torpedo from its course, attracting the same until contact is made and thence holding it extended.

These and other like objects are attained by the novel construction and combination of parts hereafter described and shown in the accompanying drawings, forming a material part of this disclosure, and in which—

Figure 1 is a side elevational view of a ship indicating the attachment of the invention.

Fig. 2 is a top plan view of the same.

Fig. 3 is an enlarged front view indicating the application of the invention, both in an extended and folded position, and

Fig. 4 is a diagrammatic view illustrating the electrical and magnetic elements, together with their connections.

The ship 10, here shown to be of conventional type and provided with the usual appendages throughout, has secured at a convenient point upon its deck raised elements 11, in which are contained powerful hoists or winches (not shown) and from which lead cables 14, running over pulleys 15 and 16, the latter being attached to the

gunwales of the ship and at either side thereof, the cables being attached at their outer ends to the outermost floats adjacent to the hooked brackets 18, supported by the floats 20, 21 and 22, which are held spacedly apart by interengaging connections 24 and strips 25, the inner ends of which are connected by brackets 27 with the hull of the vessel in the manner of a hinge, thereby permitting the same to be raised into a substantially vertical position as indicated by the broken lines shown in Figs. 2 and 3, or extended at length as shown by the full lines in the same view.

These floats, which are preferably hollow metallic tubes with oval pointed ends, are made in two sections insulated from each other by plates 30 of non-magnetic material, and are capable of sustaining the weight of pairs of magnets 32 and 33 arranged in tandem, from the lower of which extend the links of a chain cable 35 to any desired distance.

In the diagram shown in Fig. 4, a generator 40 is connected by a conductor 41, to the upper pair of magnets 32, joined by the connection 42, the return current from the lower magnet 33 of which passes through the wire 44 to the generator.

A secondary current, formed by the battery 47 and controlled by the switch 48, is connected by the wire 50, with the chain 35, the return from which comes through the wire 51 upon the close approach of, or contact with a metallic body, and causes an audible signal, as the bell 52, to be sounded upon the approach of any electrical conductor, as a floating mine or torpedo, hence announcing its dangerous proximity.

Obviously, the generator 40 will be operated only when within a zone of danger, and it will be equally apparent that the effects of the magnets 32 and 33 as communicated to the chain 35, may be sufficient to attract any metallic article and cause it to adhere at a point remote from the walls of the vessel.

Having thus described our invention what we claim as new and desire to secure by Letters Patent, is—

In combination with a ship, and a source of electrical power carried thereby, brackets secured to the sides of the hull of said ship, pairwise arranged arms hingedly connected to said brackets, sectional floats of varying diameters arranged in spaced relation upon

said arms, plates of nonmagnetic material insulating the sections of said floats from each other, pairs of powerful electromagnets arranged in tandem and carried by the outermost of said floats, connections between said source of electrical power and said electromagnets, whereby the same are energized, a chain cable extending from the lowermost of said electro-magnets into the water 10 to a predetermined depth, for attracting

magnetic material in their neighborhood, cables connecting the outermost of said floats with the ship, and hooks on said brackets engaging the uppermost of said electromagnets for allowing a raising and lowering of the floats as occasion requires. 15

In testimony whereof we have affixed our signatures.

JOHN PIES.
SOPHIE PIES.
